CLAIM

The ornamental design for a handcart, as shown and described.

DESCRIPTION

FIG. 1 is a rear, left, top perspective view of a handcart, showing my new design;

FIG. 2 is a front, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 1;

FIG. 11 is an enlarged view of detail 11 in FIG. 7;

FIG. 12 is a rear, left, top perspective view thereof in an alternate configuration;

FIG. 13 is a rear, left, top perspective view thereof in an alternate configuration;

FIG. 14 is a rear, left, top perspective view thereof in an alternate configuration;

FIG. 15 is a rear, left, top perspective view thereof in an alternate configuration;

FIG. 16 is an enlarged view of detail 16 in FIG. 14; and,

FIG. 17 is an enlarged view of detail 17 in FIG. 15.

The dashed broken lines in the figures are for the purposes of illustrating portions of the handcart and form no part of the claimed design.

The dash-dot-dash broken lines are for notating enlarged views and form no part of the claimed design.
